DESIGN FOR A DISPLAY BOX OR SIMILAR ARTICLE

John A. Clemens, Providence, R. I., assignor to Davol Rubber Company, a corporation of Rhode Island

Application November 15, 1938, Serial No. 81,106

Term of patent 14 years

To all whom it may concern:

Be it known that I, John A. Clemens, a citizen of the United States, residing at Providence, Rhode Island, in the county of Providence and State of Rhode Island, have invented a new, original, and ornamental Design for a Display Box or Similar Article, of which the following is a specification, reference being had to the accompanying drawing, forming part thereof.

In the drawing:

Fig. 1 is a perspective view of a display box or similar article, showing my new design;

Fig. 2 is a perspective view of the cover of the display box; and

Fig. 3 is a perspective view of the display box without the cover.

I claim:

The ornamental design for a display box or similar article, substantially as shown.

JOHN A. CLEMENS.
